UNITED STATES PATENT OFFICE.

EDGAR F. SIMMONS, OF ROSLINDALE, MASSACHUSETTS.

PACKING-FORM FOR LADIES' WAISTS AND SIMILAR ARTICLES.

No. 824,281.

Specification of Letters Patent.

Patented June 8, 1909.

Application filed February 7, 1908. Serial No. 415,252.

To all whom it may concern:

Be it known that I, EDGAR F. SIMMONS, a citizen of the United States of America, and a resident of Roslindale, in the county 5 of Suffolk and State of Massachusetts, have invented certain new and useful Improvements in Packing-Forms for Ladies' Waists and Similar Articles, of which the following is a specification.

- 10 In packing ladies' waists and similar garments into boxes for transportation it is customary to separate the back and front of the garment by means of crushed soft paper or some similar material in order to prevent 15 loss of shape to the garment and its becoming wrinkled. This makes considerable trouble, consuming considerable time in properly filling the garment with this material, while there is considerable expense entailed 20 in providing the necessary amount of material to properly fill out the garment.

To overcome this objection and provide a ready means of giving a proper form to such a garment when packed for transportation is 25 the object of the present invention which consists in providing a blank of flexible material which is so shaped that it may be readily made to assume a form adapted for insertion within the garment with one end 30 thereof raised to conform to the usual bust thereof.

It consists further in certain novel features of construction and arrangement of parts which will be readily understood by 35 reference to the description of the drawings and to the claims hereinafter given.

Of the drawings: Figure 1 represents a blank of flexible material embodying the features of the present invention. Fig. 2 40 represents a plan of the same with the extensions thereof locked together into the form in which it is adapted for use. Fig. 3 represents a side elevation of the same when subjected to pressure as when in use in a 45 garment, and Fig. 4 represents an end view thereof.

Similar characters designate like parts throughout the several figures of the drawings.

50 In the drawings, 10 represents a suitable blank of flexible material, at one end having a V-shaped notch 11 and at the opposite end being provided with two triangular incisions 12 which form a tapered central extension 13 on each side of which is a side extension 14. The extension 13 is provided

near each edge with a slit 15 extending through the same while each of the side extensions 14 is provided with a tongue 16 or other fastening device which is adapted 60 to pass through the slit 17 to lock the extensions 13 and 14 together when desired. These blanks 10 may be of any size to adapt themselves to different sizes of garments and the shape thereof may vary without affecting 65 the principles of this invention. For transportation and storage in the store or factory, where they are to be used they may be packed in solid stacks in flat form thus occupying but little space. When, however, 70 it is desired to pack a garment for transportation one of the blanks 10 is taken and the side extensions 14 are bent into the position shown in Fig. 2 with the tongues 16 thereof extending upwardly through the slits 75 15 in the extensions 13, these tongues 16 thereby locking the extensions 13 and 14 together so that the blank is prevented from returning 80 to its normal flattened condition. This bending in of the extensions 14 and locking them 85 to the central extension 13 causes a swelling or raised portion 17 to be formed near one end of the article, which raised portion 17 conforms to the bust of the garment and prevents it from being crushed out of shape or 90 wrinkled in transit. The lower end 18 of the article when inserted between the front and back of the garment keeps the lower end of the garment also in good condition.

By using a form of this kind much loss 95 of time is avoided in packing a garment while the shape of the garment itself is retained in better condition than would be the case when packed under the usual conditions. Moreover, when the garment is removed 100 from the box in the usual method of packing, the mass of crushed paper removed from the garment litters up a room, while with the packing form forming the subject-matter of the present application no litter 105 is made as the form may quickly be removed from the garment and preserved for further use if desired or it may be destroyed without much loss as the material from which the packing form is made is inexpensive.

It is believed that the many advantages of a packing form of the character herein described will be fully apparent without any further description.

Having thus described my invention, I 110 claim:

1. As a new article of manufacture, a

flexible paste-board blank normally flat provided with a central V-shaped incision at one end and at the opposite end with a V-shaped incision on either side of a central line and extending inwardly less than half the length of the member, thereby forming three longitudinal extensions, the center one of which is provided with slits, parallel with the adjacent sides thereof and adapted to be engaged by locking tongues, said locking tongues being ear-shaped and provided on the side extensions causing that end of said blank to be forced outwardly and to assume a shape adapted for use in a lady's waist to retain the shape of the breast portion while the main body thereof remains flat during transportation in the ordinary packing box.

2. As a new article of manufacture, a collapsible form adapted to retain the shape of

a lady's waist during transportation, having a raised breast portion at one end, formed by three extensions of which the central extension has slightly tapering sides and a blunt end, and is provided with two slits extending longitudinally and parallel to the adjacent sides thereof, each side extension being provided with oppositely and outwardly curved slits forming opposing ears and adapted to engage with the slits in the central extension to temporarily lock the extensions together.

Signed by me at 7 Water St., Boston, Mass., this 30th day of January, 1908.

EDGAR F. SIMMONS.
